METHOD OF OPERATING A SEWING MACHINE WORK JOGGING ATTACHMENT

John P. Enos, Union, N.J., assignor to The Singer Company, a corporation of New Jersey

Original application Dec. 3, 1959, Ser. No. 857,224, now Patent No. 3,121,410, dated Feb. 18, 1964. Divided and this application Feb. 26, 1962, Ser. No. 175,621

1 Claim. (Cl. 112—266)

This invention relates to work shifting attachments for sewing machines, and more particularly to a novel and improved method of operating a sewing machine having a work shifting attachment applied thereto to produce covering stitches for darning or embroidery work.

This application is a division of my United States patent application No. 857,224, filed December 3, 1959 and now Patent No. 3,121,410.

It is an object of this invention to provide a novel and improved method for producing unique darning or embroidery stitches.

A further object of this invention is to provide darning or embroidery stitches by a novel method of operation of a work jogging attachment in conjunction with a zigzag sewing machine having a bight controlling means which may be adjusted to reduce the bight of needle zigzag motion to zero and a neutral position control accessible for manual adjustment.

With the above and additional objects and advantages in view as will hereinafter appear mechanisms suitable for practice of the method of this invention is hereinafter described in the accompanying drawings in which:

FIG. 1 represents a front perspective view of a zigzag sewing machine having a work jogging attachment applied thereto in readiness for the practice of the method of this invention,

FIG. 2 represents an enlarged top plan view of the needle vibrating mechanism including the bight and neutral position controlling means of the sewing machine of FIG. 1,

FIG. 3 represents a cross-sectional view taken substantially along line 3—3 of FIG. 2,

FIG. 4 represents a cross-sectional view taken substantially along line 4—4 of FIG. 1 with the machine frame illustrated in vertical cross section,

FIG. 5 represents a cross sectional view taken substantially along line 5—5 of FIG. 4,

FIGS. 6, 7 and 8, inclusive, represent diagrammatic views illustrating various positions of the mechanism disclosed essentially in FIG. 1,

FIG. 9 illustrates the stitch paths of a group of two overlapping stitch tacks produced by the mechanism illustrated in FIG. 1 when operated in accordance with the method of this invention,

FIG. 10 represents a top plan view of the attachment illustrated in FIG. 1 with the cover in horizontal cross-section and the pattern rack removed,

FIG. 11 represents a right side elevational view of the attachment with the cover illustrated in vertical cross-section and with the lid open,

FIG. 12 represents a left side elevational view of the attachment with a cover illustrated in vertical cross-section and with the lid open and,

FIG. 13 represents a bottom plan view of a pattern rack.

Referring to the drawings, the work shifting attachment 20 used in the practice of this invention is illustrated in FIG. 1 as applied to a zigzag sewing machine indicated generally as 21. The attachment is secured by means of a thumb nut 22 to a presser bar 23 of the sewing machine carried in the bracket arm portion 24 of the sewing machine frame, and is adapted to clamp a work fabric

2

in place on a feed cover plate 25 carried on the bed portion 26 of the sewing machine frame. By means of an attachment drive lever 27 which embraces a cylindrical boss 28 of the needle clamp 29 carried on the sewing machine needle bar 30 the attachment, as will be hereinafter described, is capable of shifting a work fabric in a closed path relatively to the needle 31.

The work shifting attachment illustrated in the drawings is of the type more fully disclosed in my co-pending United States application Serial No. 857,224, filed December 3, 1959 to which reference may be had for a more detailed disclosure. For an understanding of this invention the following description of the attachment will be sufficient.

Referring to FIGS. 10, 11 and 12, the work shifting attachment is assembled on an attachment frame 40 having a raised block 41 formed with a seat 42 to accommodate the sewing machine presser bar. The block 41 is formed with spaced upstanding ears 43 in which is journaled a pivot stud 44 carried by the attachment drive lever 27. The pivot stud is retained in the ears 43 by means of a headed screw 45. Rearwardly of the upstanding ears 43, the attachment frame is formed with a clearance aperture 46 for the feed blade, indicated generally as 50. Four upstanding posts 51 are formed on the attachment frame, the posts at each side being spanned by rails 52.

The feed blade 50 is formed with a forward portion 53 having bifurcations 54 between which is pivoted a work engaging foot 55. A rear portion 56 of the feed blade is offset upwardly and connected to the forward portion by a vertical portion 57. The feed blade is disposed on the attachment frame with the rear portion 56 bearing upon the rails 52, the vertical portion 57 extending through the clearance aperture 46, and the forward portion 53 extending beneath the attachment frame.

The feed blade is slidably pivoted to the attachment frame, that is, pivoted for swinging movement in the direction of the needle jogging movement of the sewing machine, and slidable for movement in a direction transversely of that of the needle jogging movement. The forward portion 53 of the feed blade is formed with a slot 60 extending lengthwise of the feed blade. Extending lengthwise of the attachment frame 40 is a slot 61. The shouldered shank portion 62 of a fulcrum pin 63 extends through both slots 60 and 61 to slidably pivot the feed blade to the frame. The fulcrum pin 63 is embraced by an angle bracket 64 by which the pin may be selectively positioned along the slot 61. One limb of the angle bracket abuts the floor of the attachment frame 40 while the other limb abuts a raised rib 65 providing a sidewall of the attachment frame. The rib 65 is formed with a slot 66 to accommodate a threaded stud 67 extending from the angle bracket 64. A knurled nut 68 threaded on the stud 67 serves to clamp the angle bracket and thus the fulcrum pin 63 in selected position relatively to the attachment frame. The fulcrum pin is maintained in the slots 60 and 61 and on the angle bracket 64 by means of a beehive spring 69 held on the fulcrum pin by means of a nut 70.

Journalized in the attachment frame 40 is a manual ratcheting lever 87 formed with a finger grip 88 which extends beyond the attachment frame. The lever 87 is biased into a retracted position against one of the upstanding posts 51 of the frame by means of a spring 89 secured at one end to the lever and at the other end to the attachment frame. Pivoted on a bracket 90 carried on the ratcheting lever 87 is a pawl 91 biased inwardly by a spring 92.

Journalized in the attachment frame 40 coaxially with the manual ratcheting lever 87 is a pawl carrier 93 to which a pawl 94 is pivoted. The pawl 94 is biased inwardly by

a spring 95 acting between the pawl and the pawl carrier. A link 96 loosely pivoted as at 97 to the pawl carrier is pivoted in turn at 98 to the drive lever 27 such that the pawl carrier 92 will be oscillated in timed relation with the endwise reciprocation of the sewing machine needle bar.

Journaled in the attachment frame 40 is a ratchet wheel 100 formed integrally with a small pinion 101. The ratchet wheel 100 is engaged by the bifurcated arms 102 and 103 of an arched leaf spring 104 secured to the attachment frame and thus pressed firmly downwardly against the pawl carrier 93. The pawl 91 on the manual ratcheting lever 87 and the pawl 94 on the pawl carrier 93 are both disposed in operative engagement with the ratchet wheel 100 and each is arranged to override the other in turning of the ratchet wheel in one direction, thus providing clutch means effective operatively to interconnect the oscillatory pawl carrier 93 to the pinion 101 in only one direction of turning movement of the pawl carrier, the spring arms 102 and 103 serving to prevent retrograde motion of the ratchet wheel.

The rear portion 56 of the feed blade 50 is formed with an aperture 110 adapted to accommodate, with clearance on all sides, the body portion 111 of a template indicated generally as 112 and best illustrated in FIG. 13. The body portion of the template is formed with an endless groove 113 in the shape of the tack of stitches to be formed. As illustrated in FIG. 13, the groove 113 may be made in the shape of an eyelet end buttonhole or it may be of plain oval or rectangular shape. Encompassing the groove 113, and of the same general shape, is an endless rack 114 formed in the template. A plurality of ears 115 are formed on the template extending from the body portion 111 thereof and arranged to span the aperture 110 to support the body portion of the template within the aperture. Depending pins 116 formed on two of the ears 115 seat in holes 117 formed in the rear portion 56 of the feed blade to locate the template accurately in the aperture 110.

When the template 112 is properly positioned on the feed blade, the pinion 101 will be in mesh with the endless rack 114 of the template. The template may be readily removed and exchanged since it is separable from the pinion 101 and from the feed blade simultaneously by a vertical movement of the template. The feed blade aperture 110 is preferably formed with enlarged portions 120 at each side to admit an operator's finger tips at each side of the template for convenient removal and replacement of templates.

The attachment frame 40 and the actuating mechanism thereon is enclosed by a cover indicated as 130 which is preferably made of sheet metal and is secured to the attachment frame by screws 131 and 132. The cover is formed with an opening 133 which exposes the template 112 in any position of the feed blade. The cover opening is fitted with a lid 134 hinged at 135 to the cover and provided with pivoted keeper 136 which may be turned by means of a knob 137 to secure the lid in closed position.

In operation, the feed blade and the work engaging foot 55 carried thereby, will be shifted progressively in a closed path by the endwise reciprocation of the sewing machine needle bar by way of the pinion 101 to which an increment of turning movement is imparted at each needle bar stroke. Since both the pinion 101 and the fulcrum pin 62 for the feed blade are fixed with respect to the frame during operation of the attachment, no stitch-by-stitch lateral vibration of the work engaging foot is possible. The work engaging foot partakes only of progressive movement about a closed path as determined by the shape of the endless groove 113 and rack 114 of the template 112, the zigzag stitches being performed and controlled solely by the sewing machine.

As illustrated in FIG. 1, the attachment 20 of this invention is shown applied to a zigzag sewing machine of

the type disclosed in the United States Patent No. 2,852,468, December 2, 1958 to which reference may be had. This sewing machine includes a pair of coaxially arranged handles 150 and 151 for controlling the axial position of a pair of cam followers 152 and 153 respectively so that the cam followers may be positioned each into engagement with a selected one of a plurality of cam disks 154 rotatable with a sleeve 155 journaled in the sewing machine bracket arm or into engagement with a selected one of a plurality of circular cam surfaces 156, 157 or 158 formed on an annular member 159 carried concentrically on the sleeve 155.

The cam followers 152 and 153 are adapted also to engage the front face 160 of a motion integrating plate 161 which is pivotally supported on trunnion pins 162 carried in a yoke 163 formed on a pitman 164 which as illustrated in FIG. 2 is pivoted as at 165 to the swinging needle bar gate 33.

Fixed in the yoke 163 is a spherical guide head 166 embraced in a cylindrical guide aperture 167 formed in field selector member 168 carried on the annular member 159. A handle 169 extends from the annular member 157 outwardly through an aperture 170 in the machine frame where the handle 169 is accessible to the machine operator.

When the coaxial handles 150 and 151 are positioned as illustrated in FIG. 2, the cam followers 152 and 153 will be positioned in engagement with the circular cam surfaces 156 and 158, respectively, of the annular member 159. The cam followers 152 and 153 will not vibrate in this position of adjustment and, therefore, the bight or stitch-by-stitch zigzag motion of the sewing machine needle bar will be reduced to zero.

FIGS. 6, 7 and 8, however, illustrate the effect upon the needle bar 30 of movement of the handle 169 when the handles 150 and 151 are positioned as illustrated in FIGS. 1 and 2. Turning of the handle 169 will shift the neutral position of the needle bar between extreme left and right hand position thereof.

The work engaging foot 55 of the attachment 20, as is illustrated in FIG. 1, may be arranged opposite to an auxiliary feed cover plate 180 which is secured onto the feed cover plate 25 regularly supplied on the machine and provides a larger surface in opposition to the work engaging foot of the attachment. Since the attachment provides an orbital motion to the work engaging foot 55 in a closed circuitous path with no stitch-by-stitch zigzag motion, and the sewing machine is adjusted such that no zigzag motion is imparted to the needle, the attachment will shift the work in a closed buttonhole shaped path when the machine is operated.

If the handle 169 is initially positioned in one extreme position of adjustment and then gradually adjusted by the operator to the opposite extreme position of adjustment in regular increments preferably one increment during each orbital cycle of motion of the work engaging foot of the attachment, the result will be a tightly packed scroll or spiral tack of stitches. As illustrated in FIG. 9, this type of stitch tack, which may be made effortlessly and quickly by the method above described, is particularly suited to darning and embroidery work. Since the stitches of the spiral group may be made with perfect alignment and with particularly even spacing, smooth flat darning and embroidery work may be performed with this arrangement. The parallel lines of stitches made in any one stitching operation may be locked together by superimposing a succeeding tack at right angles thereon. The maximum width of any one darning or embroidery tack made as described above is the combined width of the orbital path of motion of the attachment 20 plus the total range of neutral position of the sewing machine needle. The length of any one particular darning or embroidery tack will depend upon the size of the template 112 which is inserted in the attachment.

The tacks may be combined of course one alongside the other to fill any desired space.

Having thus set forth the nature of the invention, what I claim herein is:

The method of manipulating a zigzag sewing machine having a bight control means for determining the extent of lateral jogging of the sewing needle and a neutral position control member accessible to the machine operator for adjusting the lateral position of the sewing needle in the zero position of said bight control means, and a work shifting attachment actuated by said sewing machine for imparting stitch-by-stitch movement to the work fabric in a predetermined closed path relatively to the sewing machine frame, comprising, operating the sewing machine with the work shifting attachment applied thereto and the sewing machine bight control means set at the zero position of adjustment, and simultaneously shifting the

neutral position control member in one direction from one extreme position to the other in regular increments, one increment during each traverse of the predetermined closed path of the work fabric under the influence of said work shifting attachment.
